UNITED STATES PATENT OFFICE

2,470,035

SQUARE

Clyde Hudkins, Moundsville, W. Va.

Application January 10, 1946, Serial No. 640,329

2 Claims. (Cl. 33—112)

1

My invention relates to improvements in squares for use in carpentry work, and the like, the primary object in view being to provide a simply constructed, inexpensive, folding square adapted for a wider range of use than present types of squares, and for maintaining absolutely true regardless of wear.

Another object is to provide a square adapted for use compass-wise with a carpenter's pencil as a stylus and for describing circles with radii measured in inches and fractions thereof.

Other and subordinate objects, also comprehended by my invention, together with the precise nature of my improvements, and the manifold advantages thereof will be readily understood when the succeeding description and claims are read with reference to the drawings accompanying and forming part of this specification.

In said drawings:

Figure 1 is a view in plan, partly in section, 20 of my improved square,

Figure 2 is a fragmentary similar view looking at the opposite side of the square,

Figure 3 is another similar view showing the blade folded,

Figure 4 is a view in end elevation with the blade folded, and

Figure 5 is a fragmentary view in plan of the blade.

Reference being had to the drawing by numerals, my improved square in the preferred illustrated embodiment thereof, comprises an oblong rectangular handle 1 of metal or wood, provided in one end, in the median plane of the handle, with a transverse slot 2. A longitudinal slot 3 is also provided in the handle 1, in one side edge thereof and which extends from the slot 2 to the opposite end of the handle in a common plane with the slot 2. The opposite side edge 4 of the handle 1, and which constitutes the working edge for positioning against the work, has countersunk therein a spirit level 5, of the usual type. A metal facing strip 6 extending along said working edge 4, from the bottom of the slot 2, covers the spirit level 5 with the exception of a sight opening 7 in said strip for viewing said level 5 therethrough. Screws 8 fasten the spirit level 5 in place. Screws 9 fasten the facing strip 6 in place and are extended through longitudinal slots 10 in said facing strip 6 which provides for endwise adjustment of said strip 6 for a purpose presently seen.

An oblong, straight edge, metal blade 11, of the same width as the handle 1, is pivoted at one end, as at 12, in the slot 2 for swinging into

2

the slot 3 into folded position, or, out of said slot 3 either into alignment with the handle 1 or into right-angular relation to the working edge 4 of said handle, the arrangement being such that when said blade 11 is aligned with said handle, its side edges align with the side edges of said handle to form straight edge extensions of the side edges of the handle, and when said blade 11 is swung into right-angular relation to the working edge 4, one side edge of said blade 11 extends outwardly of the slot 2 to expose all of said edge and the other side edge of said blade 11 abuts one end of the facing strip 6 so that said end forms a stop establishing the right-angular position of the blade. A screw 13 with a swiveled finger grip 13' thereon extends through the slotted end of the handle 1 and through an arcuate slot 14 in the pivoted end of the blade 11 for clamping said plate in different positions.

One edge of the blade 11 is graduated, as at 15, on both sides thereof in inches and fractions of an inch and for the usual purpose. The opposite side edge, hereinafter referred to as the inner side edge, is provided with a row of oblong openings 16 therein spaced apart along said edge in one-half inch spacings as shown. The openings 16 are of the proper size to receive therein the usual flat lead of a carpenter's pencil, not shown, and are arranged, preferably, with their longer axes disposed transversely of the blade 11. A through center opening 17 is provided in the handle 1, which, in the right-angular position of the blade 11 is aligned with a row of openings 16 and is spaced one-half inch from the nearest opening 16 of the row. A similar opening 18 is provided in the blade 11 to register with the opening 17.

A second row of openings 19, similar to the openings 16 and similarly spaced apart in one-half inch spacings, is provided in the longitudinal center of the blade 11, and a row of center forming openings 20 is provided in the longitudinal center of the handle 1. The openings 16, 19, as shown, are aligned transversely of the blade 11 with appropriate graduations 15 and are shown as arranged one-half inch apart in each row for illustrative purposes only.

The blade 11 is graduated at its pivoted end, as at 21, on one side, for angular adjustment of said blade with the graduations reading against the end of the handle 1 to which the blade 11 is pivoted. The nearest openings in the rows 19, 20 are arranged as shown to be three inches apart when the blade 11 is aligned with the handle 1 and said openings 20, as shown, are

3

spaced one inch apart but such spacing may be varied as will be understood.

The described square may be used for ordinary purposes and additionally as follows: With the blade 11 in right-angular position, various circles may be described by using a nail, or the like, in the opening 17, to provide a pivot point, inserting the lead of a carpenter's pencil in any selected opening 16, and swinging the square about the pivot provided as described. Thus, circles of various radii beginning with one-half inch and increasing in one-half inch increments may be described by selective insertion of the lead of the pencil in the opening 16, as will be clear. With the blade 11 aligned with the handle 1, and using the openings 19 and 20, in the same manner, circles may be also described starting with a radius of three inches and increasing either in one-half inch increments by selective use of the openings 19, or, in inch increments by selective use of the openings 20, or, in inch and one-half increments by selective use of the openings 19 and 20. The openings 20 are appropriately numbered to indicate the diameter of circles which may be described by using either with the nearest opening 19. By adjusting the facing strip 6, the blade 11 may always be maintained in the right-angular position to the handle 1, or the working edge 4, when said blade is swung against the stop forming end of the strip, regardless of wear on the pivot 12 of the blade 11.

With the blade 11 in right angular position to the handle 1, the square may be used to accurately place saw-cut lines, for instance, for rip sawing, by placing the handle against one side edge of the work with the blade 11 crosswise on the same, inserting a pencil point in a selected opening 16 or 19 and drawing the square along the work.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a square of the class described, an oblong handle having a working side edge with a longitudinal slot in the other side edge thereof, an elongated blade of the same width as said handle pivoted at one end in one end of the handle for

5 folding edgewise into said slot and unfolding selectively out of said slot into right angular relation to said working edge or into longitudinal alignment with said handle with opposite side edges of the blade aligned with opposite side edges of the handle, a facing strip on said working edge having a stop forming end engaged by said blade when said blade is unfolded into right angular relation, and means for adjustably securing said strip to said working edge to vary the position of said stop forming end and true up said blade in said right angular position of the same.

10 2. In a square of the class described, an oblong handle having a working side edge with a longitudinal slot in the other side edge thereof, an elongated blade of the same width as said handle pivoted at one end in one end of the handle for folding edgewise into said slot and unfolding selectively out of said slot into right angular relation to said working edge or into longitudinal alignment with said handle with opposite side edges of the blade aligned with opposite side edges of the handle, a facing strip on said working 15 edge having a stop forming end engaged by said blade when said blade is unfolded into right angular relation, and means for adjustably securing said strip to said working edge to vary the position of said stop forming end and true up said blade in said right angular position of the same, said end of the handle being cross slotted to straddle the pivoted end of the blade for clamping engagement therewith to hold said blade in unfolded positions and provided with a 20 clamping screw for clampingly engaging the same with the pivoted end of the blade, said pivoted end of the blade having an arcuate slot therein receiving said screw to permit said blade to be unfolded.

40

CLYDE HUDKINS.
